(57) **CLAIM**

The ornamental design for combined pump gear box bearing retainers and drive shafts, as shown and described.

DESCRIPTION

FIG. 1 is a perspective view of the combined pump gear box bearing retainers and drive shafts, particularly showing the inventive design thereof;

FIG. 2 is a front view thereof;

FIG. 3 is a right side view thereof;

FIG. 4 is a left side view thereof;

FIG. 5 is a top view thereof; and,

FIG. 6 is a detail view of FIG. 1.

It being understood that the broken lines are for illustrative purposes only and form no part of the claimed design.

1 Claim, 6 Drawing Sheets

FIG. 1

FIG. 5**FIG. 6**
